MOTIVE SYSTEM

Samuel Gilbert, Verona, N. J., assignor to Eclipse
Aviation Corporation, East Orange, N. J., a
corporation of New Jersey

Application May 5, 1937, Serial No. 141,003

3 Claims. (Cl. 60—44)

The present invention relates broadly to motive devices and more particularly to a combination constituting an improved motive system of the fluid pressure type adapted to be effective under 5 predetermined conditions to deliver fluid pressure in such amount as to produce actuation of the motive device.

In combination with the motive device (motor) there is provided means for producing operating 10 pressure for the motor. This means consists of a combustible solid fuel, preferably containing sufficient oxygen to support its own combustion, the combustible solid fuel being responsible for the generation of gases under the heat derived from 15 the combustion of said fuel.

Gases of the general character generated by such fuel are known to have light density, and in order to maintain their expansion and pressure efficiency it is desirable to subject them to 20 direct contact with the flames issuing from the burning fuel. In this manner such gases may be said to be superheated, and such superheated gases are desirable in the operation of a system of this character, for gases generated at a point 25 remote to the part to be moved and transferred without superheating to a point adjacent the part to be moved, if they produced pressure sufficient to move the said part, would further cool under the expansion permitted by the moving part, and thereby cause the pressure to fall 30 off appreciably.

As a result of such pressure drop, it occasionally happens that a part of the solid fuel is not fully consumed, and the unconsumed residual 35 may remain as a gritty deposit (chiefly carbon), upon the part to be moved, or sections of its housing and associated apparatus. Objects of this invention include the provision of a method and means of dislodging such carbon deposits, so that 40 they may be blown out of the device during the gas exhaust stage of the operation, or—if not actually dislodged—at least softened to a degree that will prevent interference with the proper functioning of the movable parts of the motive system.

45 Another object is to provide a method and means of introducing, into said housing and associated apparatus, a measured quantity of a grit dislodging substance, and of propelling said substance along the same path, leading from the 50 remotely positioned fuel igniting device (breech mechanism) to the housing of the part to be moved, as that which is traversed by the burning nitrogenous powder constituting the fuel charge. In this connection the invention also includes the 55 concept of a method and means of adjusting the

breech mechanism to condition it for introduction of said grit dislodging substance.

In practicing the invention I employ as the grit dislodging substance, an oily liquid having not only the capacity of softening such gritty deposits, but also of holding the carbon content thereof in solution or suspension, so that it may more readily be carried off with the exhaust gases, while at the same time providing a sufficient amount of lubrication of the parts with 10 which it comes in contact.

Other features and objects of the invention will become apparent from inspection of the specification and drawing. It is to be expressly understood, however, that the drawing is for the purpose of illustration only, and is not designed as a definition of the limits of the invention, reference being had to the appended claims for this purpose.

In the drawing,

Fig. 1 is a view, partly in section and partly in elevation, of a motive system including a part to be moved, a breech mechanism, and a connecting conduit, all constructed in accordance with the present invention;

Fig. 2 is a perspective view of one form of screen, or grid, constituting a part of the breech assembly; and

Fig. 3 is a sectional view along line 3—3 of Fig. 2.

In carrying out the present invention, there may be provided a housing 1, of substantially cylindrical shape, having at one end thereof a flange 2 adapted to support the motor in position. Where used as a starting motor for internal combustion engines, this flange will be of such construction as to permit the motor to be bolted or otherwise secured in the desired relationship to such internal combustion engine by means of bolts 3 extending through suitable openings in the 40 flange 2 and projecting into the crank case 4 which surrounds and houses the internal combustion engine member (crankshaft or crank-shaft extension) shown at 5.

Formed on the head of the cylinder 1 is an 45 externally threaded boss 6 adapted to receive one end 7 of the charge burning unit 8, which is preferably threaded thereon, and within the cylinder is a piston 9 adapted to actuate the engine engaging clutch element 11 through the instrumentalities of motion translating elements such as those indicated in patent of Romeo Nardone, No. 1,951,032.

In the burning unit 8 there is provided a tubular grating or grid 12 adapted to permit the 55

passage of the generated gases and the flames of combustion into the lower part 7 of the unit, and thence forward to the piston 9, while preventing the passage into the cylinder of large particles of unburned solid fuel. Upon the accumulation of sufficient pressure within the housing 1, this pressure will be effective upon the piston 9 for imparting a longitudinal motion thereto.

The means illustrated in Figure 1 for obtaining the desired operating pressure comprises a firing chamber 13 illustrated as containing a cartridge 14 within which is the usual priming charge and a combustible charge. The firing chamber is also provided with a cover plate 16 effective to maintain the firing pin 17 in position. Upon actuation of the firing pin, the priming charge will be ignited, thereby serving to propel the combustible charge through the firing chamber 13 and into dome 18 from which point the burning fuel and resulting gases enter conduit 21, by way of the ported cage or grid 22, provided in lieu of, or a supplement to the grid 12 above described, and having a similar function, as well as the additional function hereinafter pointed out.

I have illustrated the firing chamber 13 as equipped with a safety device in the form of a rupturable diaphragm 23 adapted to be broken in case the pressure conditions within the system exceed the maximum pressure for which it is designed. This rupturable diaphragm 23 may be detachably held in position by a suitable nut 24, removable and replaceable therewith as may be required.

In addition to serving as a protection against excess pressure development, cap assembly 23, 24 permits ready access to the chamber 13 and conduit 21 for insertion of a capsule 26 containing the grit dislodging oil above referred to. As shown, this assembly 23, 24 also permits, when removed, manual rotation of the annular cage 22 through an arc of ninety degrees, more or less, to bring the larger, diametrically opposed, openings 28 and 29 into alignment with the conduit 21, to permit passage of the capsule 26 there-through, the normal position of said cage 22 being that in which said openings 28 and 29 are offset from the conduit opening, so that the conduit opening will normally receive only such particles of the solid fuel as can find their way through the smaller ports 31 constituting the grid or screen part of the cage. Such manual rotation of the cage 22 is of course facilitated by reason of the many apertures in the said cage, which apertures readily lend themselves to the use of any suitable tool by which the cage may be turned with re-

spect to the surfaces of the elements 13 and 18 in which it is received—there being no necessity for removal of the member 18 from the member 13 in order to permit this turning of the cage 22 whenever desired.

As shown, cap 24 threads onto a boss 33 which is identical with a second boss 34 opposite thereto, so that either boss may receive the tube fitting 36 and tube 21, while the other remains available for the cap, thus rendering the breech device, as a whole, capable of installation in two different angular relationships with respect to its supporting means 37. Moreover, while it is preferred to insert capsule 26 in the manner recited, so that it will be propelled intact as far as the grid 12, or nearly thereto, as indicated in dash lines at 41, prior to consumption of its covering, said capsule, or any equivalent thereof, may also be inserted along with the cartridge 14—that is, through the normal cartridge opening—in which event its inflammable covering (of Celluloid or the like) will be consumed in chamber 13 or 18, and only the oil contained therein will pass through cage 22 into the tube 21, unit 8 and cylinder 1.

What is claimed is:

1. In a closed system for development of fluid pressure by generation of nitrogenous gases from a nitrogenous solid charge, to actuate a part to be moved, means for dislodging carbon deposits therein comprising an inflammable capsule containing a carbon softening oil, and means for inserting said capsule into the space lying between the nitrogenous charge and said part to be moved.
2. In a system for development of pressure by the ignition of an explosive material containing carbon, which material, as it burns, produces pressure to actuate a part to be moved, means for preventing the accumulation of deposits of carbon remaining unburned, said means comprising an inflammable capsule containing a carbon softening oil releasable therefrom as the enclosing capsule is subjected to the fire of the burning carbon and consumed thereby.
3. In a closed system for development of fluid pressure by generation of nitrogenous gases from a nitrogenous solid charge, to actuate a part to be moved, means for dislodging carbon deposits therein comprising an inflammable capsule containing a carbon softening oil, and means for exploding said solid charge and thereby developing fluid pressure to act upon said capsule to propel it toward said part to be moved.

SAMUEL GILBERT.
